UNITED STATES PATENT OFFICE.

ELMER A. SPERRY, OF CHICAGO, ILLINOIS, ASSIGNOR TO THE SPERRY ELECTRIC RAILWAY COMPANY, OF CLEVELAND, OHIO.

ELECTRIC LOCOMOTIVE.

SPECIFICATION forming part of Letters Patent No. 502,020, dated July 25, 1893.

Application filed October 23, 1891. Serial No. 409,583. (No model.)

To all whom it may concern:

Be it known that I, ELMER A. SPERRY, a citizen of the United States, residing at Chicago, in the county of Cook and State of Illinois, have invented certain new and useful Improvements in Dynamos and Motors, of which the following is a specification.

My invention relates to the construction of electric machines, more especially to electric motors, and it consists in certain details of construction of the armature journal, mounting of the armature, construction of the body, or field magnet frame, support of the field coil and mounting, especially when adapted as a street car motor. These inventions are illustrated in the accompanying drawings, in which—

Figure 1 is a side elevation, partly in section. Fig. 2 is a view at right angles to Fig. 1, showing axle in fore-ground. Fig. 3 shows section of armature core with wire band. Fig. 4 is a detail. Figs. 5 and 6 show different ways of making bands upon the armature. Fig. 7 shows the alternate form of device to secure a parallel movement.

Like letters of reference indicate similar parts throughout the several views.

A indicates a U-shaped iron forging or casting, preferably the former. A' illustrates a similar portion covering the top of the U, presenting the pole piece A'' downward therefrom. The pole-piece B is supported by the U-shaped part A. The coil of the field magnet is wound on and supported between the pole piece A'' and cap A' and is indicated by B'.

B'' is a hollow armature shaft supplied with bushings C made of any lubricating non-metallic substance such as compressed graphite or the like.

C' is a stationary mandrel upon which the shaft B'' revolves; the bushing C may be stationary. The spider C'' mounted upon the armature shaft serves to secure the armature core D thereto. This core is made up of thin insulated disks as usual, slotted at D' to admit the windings D'', (see Fig. 3.) After the winding is completed the tops of the projecting teeth are overwound with insulated iron wires E, preferably in more than one layer. I have adopted two means of winding

this wire, first illustrated in Fig. 5 in which all the wires are insulated, the exterior circle representing the insulation, the other in Fig. 6 where each alternate wire is insulated the others being bare, shown at E'. In this case it is preferable, though not necessary, to make the bare wire of about the same size as the exterior of the insulation of the covered wire E. In this case, also, a septum of insulation is placed between the two layers of wires, indicated at E''. The extremities of the stationary mandrel C' are supported in brackets F, which may be either integral with the casing A' or bolted thereto, both forms being shown in Fig. 2, the bolted form being shown in Fig. 1. Upon the armature shaft B'' is mounted the pinion F', which is organized to engage the gear F'', which is mounted upon the axle G. In the case of Figs. 1 and 2 this axle is the car axle G' driving the car wheel. A journal G'' encircles the shaft G' and is carried in a segmental slot H of peculiar shape, the medial line of which forms the portion of the circumference of a circle around the center of the mandrel C'. The slot is longer than the journal G'' which fits the slot only on its two lateral curved surfaces. Shrouds are provided at H' which guide the journal longitudinally and hold it within the slot. H'' H''' represent two elastic substances, or springs, one above and one below the journal and between it and the end of the slot. The two journals G'' are coupled so as to move simultaneously and in the same direction. Fig. 2 illustrates one method of accomplishing this result consisting of the segmental rack I formed upon the two journals adapted to co-operate with the pinions I' which are mounted upon the auxiliary axle I'' in housings J, fastened to the part A of the motor. Fig. 7 illustrates an alternate form to accomplish the same result. Two segmental racks J' co-operate with two levers J'' J''' fulcrumed on the motor frame at K K' and attached to the journals G'' at point K'. L illustrates the commutator of the motor or dynamo as the case may be and L' indicates the shield which is fastened to the lower part of the body. A spring L'' supports the machine at a point opposite the axle G, there being one both above and below the projection of the motor indicated by M. The

housings M' containing the slot H are made preferably removable for obvious reasons. The dotted line at N indicates the height to which the shield rises.

- 5 The use and operation of my device are as follows: An electric machine, consists of a rigid frame-work combined with a more or less large quantity of copper wire which is covered with cotton thread used for insulation 10 and should not be subjected in whole or part to severe or sudden shocks or concussive blows. To avoid this action I mount the machine solely by elastic supports so that it will not partake of the vibration of such supports.
- 15 When power is transmitted to or from a machine so supported, by such a device, for instance as a spur gear, it becomes necessary to keep the elements absolutely in alignment for the proper working of such gearing. It 20 will readily be understood that to preserve such alignment the change of position within the slots H of the journals G'' should be equal and simultaneous. The segmental racks I, pinions I' and axle I'', are for the 25 purpose of preserving such parallelism of movement in the well known manner. The operation of the device shown in Fig. 7 accomplishes the same result. The medial line of the slot H being struck about the center of 30 the pinion F' the mesh of the gears is unchanged by a change of movement of the journals G''. To remove the armature it is simply necessary to remove the bolts N' and lift it together with the cap out of the U-shaped part A the joint being shown at O''. Where but one field coil as B' is used it becomes necessary to reduce the magnetic reluctance of the whole magnetic circuit to a 35 minimum. This I accomplish by presenting 40 to the polar surface the projecting teeth rising from the armature core and furthermore reducing so far as possible the reluctance of the air gap exterior thereto by filling the same with bands of iron wire which are insulated to prevent the generation of currents 45 therein, and are made small and more than one layer is used.
- It is preferable to use for a journal which 50 is in such close proximity to the electrical parts of the armature as that shown at C, one which requires no liquid lubrication. The 55 non-metallic sleeve C accomplishes this result and does away with the necessity of any liquid lubrication.
- 55 To prevent dust from having free access to the end of the sleeve C I have provided a dust collar which consists in a cap N'', spring O' and collar made of the same substance as the sleeve C, all of which is illustrated in Fig. 4.
- 60 It will be observed that the stationary axes C' being rigidly secured to each of the brackets F form together with them a form of truss, thereby strengthening the frame supporting the armature.
- 65 Another very essential feature will be noticed in the shortness of the machine, the

journals being interior to the armature. The boss upon the lower end of the brackets F need be only about one-third the dimension along the axis that would be required were 70 they replaced by journals.

Having thus described my invention, what I claim, and desire to secure by Letters Patent, is—

1. In an electric machine the stationary 75 axle, a rotating hollow armature shaft combined with a non-metallic sleeve between the two forming a journal bearing therefor.

2. In an electric machine, the stationary axle, a rotating hollow armature shaft combined with a non-metallic sleeve mounted 80 within and rotating with the armature shaft forming a bearing therefor.

3. In an electric machine, the stationary axle, a rotating hollow armature shaft combined with a non-metallic sleeve between the 85 two forming a journal bearing therefor and brackets for supporting the axle exterior to each end of the armature shaft.

4. In an electric machine, the stationary 90 axle, a rotating hollow armature shaft combined with a non-metallic sleeve between the two forming a journal bearing therefor, brackets for supporting the axle and dust collars applied to the ends of the armature shaft. 95

5. In an electric machine, the stationary axle, a rotating hollow armature shaft combined with a non-metallic sleeve between the 100 two forming a journal bearing therefor, brackets for supporting the axle and dust collars applied to the ends of the armature shaft consisting in part of a collar of non-metallic lubricating material similar in substance to the sleeve and requiring no liquid lubrication.

6. In an electric machine, which is mounted 105 solely upon elastic supports, power transmitting gearing connected with the rotating portion thereof in combination with a device or devices independent of such gearing adapted to confine the alignment of the axes of the 110 gearing to parallelism in at least one plane.

7. In an electric machine which is mounted 115 solely upon elastic supports, power transmitting gearing requiring alignment of axes for successful operation connected with the rotating portion thereof, in combination with a device or devices independent of such gearing adapted to confine the alignment of the axes of the 120 gearing to parallelism in at least one plane.

8. In an electric machine mounted elastically upon an axle, journals upon the axle adapted to move up or down in guides upon the machine, a parallel motion connection between such journals arranged to synchronize 125 their motion in such guides, a gear upon such axle and a co-operating gear mounted upon the rotating part of the machine.

9. In an electric machine mounted elastically upon an axle, journals upon the axle 130 working in guides upon the machine, a segmental rack upon each journal cooperating

with pinions secured to a shaft extending from one journal to the other, the shaft being mounted upon the machine.

10. In an electric machine having but one field magnet coil, a **U**-shaped forging forming one pole piece and a cap for the **U** consisting of a casting having the other pole-piece depending therefrom and provided also with brackets integral therewith supporting the armature journal and a single field coil wound and supported between the pole-piece and the cap.

11. In an electric machine having but one field magnet coil, a **U**-shaped forging form-

ing one pole piece and a cap for the **U** consisting of a casting having the other pole-piece depending therefrom and provided also with 15 brackets integral therewith supporting the armature journal and a single field coil wound and supported between the pole-piece and the cap.
